UNITED STATES PATENT OFFICE.

FRED N. ROOT, OF KALAMAZOO, MICHIGAN.

TRACK SCRAPER OR CLEANER.

1,379,363.

Specification of Letters Patent.

Patented May 24, 1921.

Application filed April 27, 1920. Serial No. 377,134.

To all whom it may concern:

Be it known that I, FRED N. Root, a citizen of the United States, residing at Kalamazoo, Kalamazoo county, State of Michigan, have invented certain new and useful Improvements in Track Scrapers or Cleaners, of which the following is a specification.

This invention relates to improvements in track scrapers or cleaners, more especially 10 for street cars.

The objects of the invention are

First, to provide a suitable yielding scraper with means for automatically locking it in down or up position.

15 Second, to provide an improved construction of spring scraper which shall yield effectively whether the car is going forward or backward.

Objects relating to details and economies 20 of construction and operation will definitely appear from the detailed description to follow. I accomplish the objects of my invention by the devices and means described in the following specification. The invention 25 is clearly defined and pointed out in the claims.

A structure which is a preferred embodiment of my invention is fully illustrated in the accompanying drawing, forming a part 30 of this specification, in which:

Figure I is a detail perspective view of my improved scraper device for street car use, as it would appear arranged for operation but detached from the framework of 35 the street car.

Fig. II is a detail perspective view of a spring and scraper shoe detached.

Fig. III is an enlarged detail sectional plan view, taken on line 3—3 of Fig. I, showing 40 details of the automatic lock.

In the drawing similar numerals of reference refer to similar parts throughout the several views.

Considering the numbered parts of the 45 drawing, 1 is the scraper shoe, 2 is the track cleaning tooth or bar disposed to engage the groove or the notch at the side of a rail. 3 is the spring which has a substantially vertical portion 3' that is extended down and 50 secured to the back of the scraper shoe. The forward end of the spring 3 is bent into the arc of a circle 3'', where it is clamped by a clip 4 to the side of the rock shaft 5. The rock shaft 5 is disposed transversely and 55 supported by brackets 6 which are secured to the under framework of the platform or

front portion of a street car. The rock shaft 5 is provided with an actuating arm 7 which is actuated by an operating link 8. The operating link 8 is controlled from the vertical 60 control column 9, which may be provided with a hand wheel 9' or a crank 9'', or any means of control, as indicated in Fig. II.

An arm 10 is securely fixed to the lower end of the column 9 and it is pivoted at 11 65 to the rear end of the operating link 8. The lower end of the column 9 is pivoted at 13 on the supporting angle iron brackets 12 through the horizontal portion 12' of the 70 said angle iron bracket and at a little distance from the vertical member thereof.

The link 8 is notched at 14 so that the pivot 11 passes the dead center when the control column 9 is manipulated. It will thus be seen that when the scraper is thrown down 75 to its work, strong spring pressure is applied and because the rock shaft yields in this application, when the arm 10 swings so that the pivot 11 passes the dead center, the device is automatically locked in its down 80 position for scraping. On the other hand, when the arm 10 is thrown to the opposite position it passes the dead center when it contacts with the vertical portion of the angle bracket and the scraper is locked in 85 its elevated position.

Because of the fact that the scraper is attached to a vertical portion of the rearwardly - extending horizontally - disposed spring, the same can yield and tilt either 90 forward or back and readily pass obstructions on the track.

I have described my improved structure in its simplest form and desire to state that it can be applied and made use of even when 95 power means and cushioning devices are made use of, but as my invention does not pertain to the same I have not illustrated such details here. I desire to claim the structure in the specific form here illustrated and also broadly, as pointed out in the appended claims.

Having thus described my invention, what I claim as new and desire to secure by Letters Patent is:

1. In a track scraper, the combination of 100 a scraper shoe, a blade spring carrying the same having a vertical portion to which the said scraper blade is attached and a substantially horizontal portion, a rock shaft, 110 means for securing the end of said spring to said rock shaft, an actuating arm on said

rock shaft, a connecting link to said arm, a vertical control column, and an arm at the lower end of said column, pivotally connected to said link to form a toggle joint, arranged to pass the dead center, said link being notched to permit the pivot to pass the dead center to hold the scraper in its up or down position, coacting as specified.

2. In a track scraper, the combination of 10 a scraper shoe, a blade spring carrying the same, a rock shaft, means for securing the end of said spring to said rock shaft, an actuating arm on said rock shaft, a connecting link to said arm, a vertical control column, and an arm at the lower end of said column, pivotally connected to said link to form a toggle joint, arranged to pass the dead center, said link being notched to permit the pivot to pass the dead center to hold the scraper in its up or down position, 20 coacting as specified.

3. In a track scraper, the combination of a scraper shoe, a blade spring carrying the same having a vertical portion to which the 25 said scraper blade is attached and a substantially horizontal portion, a rock shaft, means for securing the end of said spring to said rock shaft, an actuating arm on said rock shaft, a connecting link to said arm, 30 a vertical control column, and an arm at the lower end of said column, pivotally connected to said link to form a toggle joint, arranged to pass the dead center, coacting as specified.

35 4. In a track scraper, the combination of a scraper shoe, a blade spring carrying the

same having a vertical portion to which the said scraper blade is attached and a substantially horizontal portion, a rock shaft, means for securing the end of said 40 spring to said rock shaft, an actuating arm on said rock shaft, a vertical control column, and means connecting said column to said rock shaft, coacting as specified.

5. In a track scraper, the combination of 45 a scraper shoe, a rock shaft, spring connections from said rock shaft to said scraper shoe, an actuating arm on said rock shaft, a connecting link to said arm, a vertical control column and an arm at the lower end of said column, pivotally connected to said link to form a toggle joint, arranged to pass the dead center, said link being notched to permit the pivot to pass the dead center to hold the scraper in its up or down position, 50 coacting as specified.

6. In a track scraper, the combination of a scraper shoe, a rock shaft, spring connections from said rock shaft to said scraper shoe, an actuating arm on said rock shaft, 55 a connecting link to said arm, a vertical control column, and an arm at the lower end of said column, pivotally connected to said link to form a toggle joint, arranged to pass the dead center, coacting as specified.

In witness whereof, I have hereunto set my hand and seal in the presence of two witnesses.

FRED N. ROOT. [L.S.]
